UNITED STATES PATENT OFFICE.

DAVID THOMPSON, OF PHILADELPHIA, PENNSYLVANIA.

BEDSTEAD COVERING.

Application filed March 4, 1927. Serial No. 172,711.

The present invention relates to an improved cover or closure for use in connection with bedsteads, the purpose being to provide an article of this character, where those lying 5 in the bed cannot be observed by others who may enter the room.

A cover of this character is also very useful in hospitals, especially in rooms having two, three and four beds, or in a public ward where 10 there are a number of beds, it being possible to dispense with the screens that are usually used between the various beds. For instance, where beds are in a row one portion of the cover on the same side of each bed may be 15 raised, permitting the occupant of the bed to observe the closed side of the adjacent bed, preventing the occupant therein from being observed.

A cover or closure of this kind may be used 20 by automobile tourists, especially those who are termed as tin-can tourists, living more or less in the open and in tents, the occupants of the bed being unobserved by those passing along the road.

Still further, a cover of this kind is made 25 to fit beds of different sizes and where the head and foot boards are of different shape, either side of the cover being adapted to be raised to permit of ingress and egress, and 30 to allow those occupying the bed to look outside when desired.

One of the features of the invention is a provision of guides on head and foot boards having a plurality of slats, the guides being 35 flexible to permit them to fit head and foot boards of different shapes and sizes, the slats including a pliable cover of any suitable weatherproof material such as canvas or the like, in order to shed the water, should the bed be in the open.

Still another feature is the inclusion of means for securing the sliding pliable cover in position on each side, to hold it down tight.

A further construction comprises means 45 to secure transverse pieces or bars to the legs of the head and foot boards to further assist in holding the cover in position, there being adjustable rod connections between the bars 50 or pieces and the flexible guides, so as to re-

tain the parts in firm fitting position to the bed.

It is to be understood that the particulars herein given are in no way limitative and that while still keeping within the scope of the 55 invention, any desired modification of details and proportions may be made in the construction of the device according to circumstances.

The invention comprises further features and combinations of parts to be hereinafter 60 set forth, shown in the drawings and claimed.

In the drawings:—

Figure 1—is a view in perspective of an improved cover for bedsteads showing it applied to a bed. 65

Figure 2—is a side elevation of the bed cover, but showing the canvas covering removed.

Figure 3—is an end view showing the foot-board of the bed with the cover applied. 70

Figure 4—is a plan view of the bedstead canopy with the canvas cover removed.

Figure 5—is an enlarged detail view of the inner face of either the headboard or the footboard, showing the rail thereof and illustrating on an enlarged scale the flexible guide for the several slats. 75

Figure 6—is an enlarged detail view of a portion of the footboard illustrating the flexible guide and the slats and also the canvas 80 cover in dot and dash lines.

Figure 7—is a detail view of the canvas covering and its slats, the rollers being spindled at the ends of the slats.

Figure 8—is a detail sectional view 85 through one of the guides and the rail of the footboard showing how the guide is mounted.

Figure 9—is a sectional view through the lowermost slat or bar of the cover, showing the spring tension devices for holding the 90 lowermost slat or bar securely in position, when the cover is lowered.

Referring to the drawings:

1 identifies a conventional type of bed having a head board 2 and a foot board 3, and fitting the two boards is a cover 4, which is made up of a plurality of slats or bars, which while being spaced, are joined in sequence by means of a canvas covering 5. Obviously 95 when the slats or bars on each side of the bed 100

are raised, thereby collapsing them together, the canvas cover arranges in folds, and when the slats are lowered the canvas stretches out and produces a comparatively smooth surface, as the canvas is on the outside of the slats.

The ends of the slats or bars have rollers 6 spindled thereon, and fitting the rails of the head and foot boards are flexible members 7. These members 7 are made up of a plurality of sequentially united links as shown, such as will flex, and permit the members to fit different shapes and sizes of rails of head and foot boards.

The several links are provided with guides 8. The guides are in the form of flanges carried by the links of the members 7 and are spaced in parallelism and grooved as shown in Figure 8 for the reception of the rollers 6 which are spindled on the slats or bars of the cover. Obviously it may be seen how the slats or bars are movable and still remain connected to the members 7. The members 7 are secured by suitable straps 9 and buckles 10 to the rails of the head and foot boards. The straps fit around the rails, and by passing certain of the straps 9 through the buckles 10 the straps may be drawn tight, holding the members 7 securely in position. It is only essential to utilize these straps 9 where the rails of the head and foot board curve downwardly to merge into the legs of the bedstead.

The lowermost slat or bar of the cover on each side thereof is tubular, and mounted in such tubular parts 11 are locking plungers 12, the shanks of which are mounted in guides 13, there being springs 14 interposed between the guides 13 and collars or discs 15 on the shanks of the plungers, to tension the latter and retain their exposed ends frictionally in contact with the bottoms of the several guides of the members 7, to retain the lower part of each side of the cover in lowered or raised positions. The shanks of the locking plungers have handles 16 which project through slots 17 in the tubular parts 11, in order to be grasped by an operator to release the locking plungers, to allow either or both sides of the cover to be raised or lowered.

Arranged adjacent the legs of the bedstead, that is below the side rails thereof and transversely of the head and foot boards are pieces or bars 18. The lower ends of the members 7 terminate in spaced arms 19, which straddle the ends of the bar 18 and are pivotally connected to said bars as shown, to hold the members in position. The members have arcuate seats 20 which engage the rails of the head and foot board, so that the members can more readily conform to the shape and size of the head and foot boards.

It is to be noted that the central link of each member 7 at the centre and the extreme

top of the head and foot boards is rigidly connected by a longitudinally extending rod 21, which assists materially in holding the members 7 in position, it being unnecessary in this instance for the use of straps 9 at the central part of the bedstead.

To insure this condition an adjustable rod connection 23 is interposed between said central links of the members 7 and the transverse bars or pieces 18. These rod connections are on the outside of the head and foot boards, therefore they overlie the rails of said boards and hence prevent any end movement of the members 7, in fact prevent any end movement of the cover as a unit.

This rod connection comprises two sections 24 and 25, the former being carried by the central link of the members 7, while the latter is connected to the transverse bar or piece 18 in any approved way, and these two sections 24 and 25 are telescopically united as shown at 26, there being a set screw 27, though any other similar device may be used, for holding the two sections 24 and 25 in different adjusted positions, in order that the entire structure of the cover for the bedstead may be fitted to beds of different sizes.

The transverse pieces or bars 18 are connected to the legs of the bedstead by U-shaped staples or holding members 28, which straddle the legs of the bedstead and have nuts 29 thereon to tighten the pieces or bars 18 in position.

The canvas cover 5 as previously stated arranges in folds when the slats or bars are collapsed to open positions. However, this cover 5 merges into head and foot board end covers 30, which overlie the links of the members 7 and hang down over the head and foot boards. These end covers are sufficiently full to hang neatly and yet allow the end covers to shirr in 105 folds when either side of the main cover is raised.

The invention having been set forth, what is claimed is:

1. A cover for bedsteads comprising flexible guides and means for mounting them upon the rails of the head and foot board of a bed, and a slat and canvas cover with means for operatively joining the slats in the guides, whereby either side of the cover may be slidably raised or lowered in the flexible guides.

2. A portable cover for bedsteads comprising flexible guides with means for mounting them upon the rails of the head and foot boards, a pliable cover operatively associated 120 with the guides, whereby either side of the cover may be slidably raised or lowered in the flexible guides, means to connect the lower ends of the guides to the legs of the bedstead.

3. A portable cover for bedsteads comprising flexible guides for the head and foot boards of the bedstead, said flexible guides constructed to operatively engage with the

upper and side margins of the head and foot board rails, rods connected centrally to both flexible guides and extending downwardly centrally of the head and foot boards, trans-
5 verse bars operatively connecting the legs of the head and foot boards respectively, the lower ends of the flexible guides connected to the extremities of the transverse bars, said

rods having adjustable connections with the transverse bars, and a pliable cover operative- 10 ly associated with and in the flexible guides, whereby either side of the cover may be raised or lowered.

In testimony whereof he affixes his signature hereto.

DAVID THOMPSON.
